E. L. EDWARDS,
X-RAY CABINET,
APPLICATION FILED JAN. 24, 1919.

1,419,241.

Patented June 13, 1922.

UNITED STATES PATENT OFFICE.

EDWIN L. EDWARDS, OF INDIANAPOLIS, INDIANA, ASSIGNOR TO EDWARDS X-RAY CORPORATION, OF INDIANAPOLIS, INDIANA, A CORPORATION OF INDIANA.

X-RAY CABINET.

1,419,241.

Specification of Letters Patent. Patented June 13, 1922.

Application filed January 24, 1919. Serial No. 272,823.

To all whom it may concern:

Be it known that I, EDWIN L. EDWARDS, a citizen of the United States, residing at Indianapolis, in the county of Marion and 5 State of Indiana, have invented a new and useful X-Ray Cabinet, of which the following is a specification.

It is the object of my invention to provide a self-contained X-ray cabinet, which can be 10 used both as a protective enclosure for the operator and as a dark room for developing the negatives, and which swingingly supports the X-ray tube and a seat for the patient so that said tube and seat may be swung 15 either into operative position outside the cabinet or into inoperative position within the cabinet.

The accompanying drawing illustrates my 20 invention: Fig. 1 is a perspective view of an X-ray cabinet embodying my invention, with the parts in operative position; Fig. 2 is a somewhat similar perspective view, showing the interior of the cabinet, and with the tube-carrying door partly broken away; Fig. 3 25 is a horizontal section through the cabinet, with the working parts within it.

The cabinet has a top 10, a bottom 11, and 30 three fixed sides 12, 13, and 14, conveniently supported on suitable feet 15, these three sides and the top and bottom and feet being relatively fixed and constituting a supporting stand. Conveniently the cabinet is of suitable height to receive a man standing up. At the free front edges of the sides 35 12 and 14 are hinged two doors 16 and 17. These two doors overlap with the door 17 outermost, as indicated in Fig. 3, so that the cabinet may be closed by such outer door 17 whether the inner door 16 is closed or open. 40 In the latter case, at least, the closing of the cabinet by the outer door 17 is preferably light-tight. The inner door 16 may be swung either to the closed inoperative position shown in Fig. 3 or to the open, operative position shown in Fig. 1, in which latter position it lies against the outer face of the side wall 12; the hinges 18 on which said inner door 16 is mounted permit swinging of the door through 270° to accomplish this. 45

50 On what is its inner surface when it is closed the inner door 16 carries near the bottom a patient's seat 19, which is preferably a suitable form of folding seat as illustrated, and near the top an adjustable support 20

for an X-ray tube 21; so that the seat and 55 tube are on what is the outer surface of the door 16 when such door is fully open and lies against the wall 12, but are folded into the space within the cabinet when such door is closed. The same face of the door 16 60 may be provided with an adjustable head-rest 22, for the patient's head. By manipulating the support 20 in the usual way, the rays from the tube 21 may be directed as desired. The terminals of the tube 21 are connected by suitable conductors 23 to the outer 65 ends of insulating posts 24 fixed to the same face of the door 16; and these posts 24 are provided with spring fingers 25 connected to the conductors 23 and arranged to engage 70 corresponding spring fingers 26 on forwardly projecting insulating posts 27 carried by the cabinet top 10. The spring fingers 26 are connected by suitable conductors 28 to the secondary terminals 29 of a suitable 75 high-tension transformer 30, mounted on the cabinet 10. Thus the connections from the X-ray tube 21 to the transformer 30 are made and broken by the swinging of the inner door 16. 80

At about the height of a man's eyes, the wall 12 is provided with a window opening 31, which may receive any desired glass 32, such as lead glass when the X-ray apparatus is in use, a ruby glass when the cabinet is 85 used for developing purposes, and an opalite glass to examine negatives. If desired, the ruby glass may be removably superposed over the lead glass, so that it may be put into or out of position at will; or the window 90 95 may be provided with glass-receiving slide-ways 33 in which either a ruby glass or a lead glass may be placed as desired. The door 16 is provided with an opening 34 which registers with the window 31 when such door is swung back against the wall 12. In order to protect the operator, a screen 100 formed by a layer of lead 35 or other material opaque to X-rays is mounted between the tube and the operator, as in the side wall 12 as shown in Fig. 3, and if desired in any of the other side walls or in the doors 16 and 17, though ordinarily such a protective layer in the side wall 12 is sufficient.

Mounted within the cabinet are the electrical 105 controlling devices, such as a switch 36 and a rheostat 37; and also mounted within the cabinet is a developing tank 38. The

developing tank is preferably on the wall 12 below the window 31, and the electrical controlling devices are preferably on the wall 13, as is clear from Figs. 2 and 3.

- 5 When the cabinet is not in use, the doors 16 and 17 are both closed, and the X-ray tube 21 and its support and the patient's seat 19 are folded within the cabinet. When the cabinet is in use, the inner door 16 is swung 10 open so that it lies against the side wall 12, thus connecting the X-ray tube 21 to the transformer 30 by the interengagement of the spring fingers 25 and 26. The patient is placed in proper position on the seat 19, 15 the support 20 is adjusted so that the rays from the tube 21 will be directed in the desired direction, and the plate or film to be exposed is put in position. Then the operator enters the cabinet, preferably closing 20 the door 17 behind him, and manipulates the controlling devices, such as the switch 36 and rheostat 37, to produce the desired exposure. Then the operator comes out and gets the exposed film or plate; and if he 25 wishes may immediately return into the cabinet and develop such film or plate in the developing tank 38, the door 17 being closed and the ruby glass being in position over the window 31 during such developing.

30 I claim as my invention:

1. An X-ray cabinet, comprising a cabinet with a swinging member, an X-ray tube mounted on said swinging member for all positions of the latter so that by the swinging of said member said tube may be swung into or out of said cabinet, and controlling devices for said tube mounted within said cabinet.

2. An X-ray cabinet, comprising a cabinet 40 with a swinging member, and an X-ray tube mounted on said swinging member for all positions of the latter so that by the swinging of said member said tube may be swung into or out of said cabinet.

- 45 3. An X-ray cabinet, comprising a cabinet provided with a swinging door, a patient's seat and a support for an X-ray tube mounted on that face of the door which is the inner face when the door is closed, and controlling devices for said X-ray tube mounted within said cabinet.

- 50 4. An X-ray cabinet, comprising a cabinet provided with a swinging door, and a patient's seat and a support for an X-ray tube 55 mounted on that face of the door which is the inner face when the door is closed.

5. An X-ray cabinet, comprising a cabinet 60 provided with a swinging door, a support for an X-ray tube permanently mounted on that face of the door which is the inner face when the door is closed, and controlling devices for said X-ray tube mounted within said cabinet.

6. An X-ray cabinet, comprising a cabinet 65 provided with a swinging door, and a sup-

port for an X-ray tube permanently mounted on that face of the door which is the inner face when the door is closed.

7. An X-ray cabinet, comprising a stand, a patient's seat foldably mounted on one side 70 of said stand at an intermediate point in the height of said side, and a support for an X-ray tube also mounted on said stand to extend over the head of a patient sitting on said seat, said support being adjustable to 75 make the X-ray tube co-operate with said patient.

8. An X-ray cabinet, comprising a cabinet having a swinging door, an X-ray tube mounted on said door, high-tension supply 80 conductors, and means controlled by the swinging of the door for connecting said X-ray tube to said high-tension supply conductors.

9. An X-ray cabinet, comprising a cabinet 85 having a swinging member, an X-ray tube mounted on said swinging member for all positions of the latter so that it may be swung either into the cabinet or outside of the cabinet, a transformer mounted on the 90 top of the cabinet, and connections from said transformer to said X-ray tube.

10. An X-ray cabinet, comprising a cabinet 95 having a swinging member, an X-ray tube mounted on said swinging member so that it may be swung either into the cabinet or outside of the cabinet, a transformer mounted on the top of the cabinet, and means controlled by the movement of said 100 swinging member for connecting said X-ray tube to and disconnecting it from said transformer.

11. An X-ray cabinet, comprising a cabinet 105 having a swinging member, an X-ray tube mounted on said swinging member for all positions of the latter so that it may be swung either into the cabinet or outside of the cabinet, a transformer mounted on the top of the cabinet, and connections from 110 said transformer to said X-ray tube, and controlling devices for said transformer located within said cabinet.

12. An X-ray cabinet, comprising a cabinet 115 having two doors which overlap when both are closed, and a support for an X-ray tube mounted on that face of the inner door which is the inner face when such door is closed, said outer door having a light-tight joint with said cabinet when said inner door is open and said outer door is closed.

13. An X-ray cabinet, comprising a cabinet 120 having an openable side formed by two overlapping doors hinged at the opposite edges of said openable side and overlapping when both doors are closed, a support for an 125 X-ray tube mounted on that face of the inner door which is the inner face when such door is closed, said inner door being openable by swinging so that what is its outer face when it is closed will when it is open 130

lie against an outer face of a fixed wall of said cabinet.

14. An X-ray cabinet, comprising a cabinet having at one side, a hinged door for closing said side, a support for an X-ray tube mounted on that face of said door which is the inner face when such door is closed, said door being openable by swinging so that what is its outer face when it is closed will when it is open lie against an outer face of a fixed wall of said cabinet.

15. An X-ray cabinet, comprising a cabinet with a swinging member, an X-ray tube mounted on said swinging member so that by the swinging of said member said tube may be swung into or out of said cabinet, controlling devices for said tube mounted within said cabinet, and a screen opaque to X-rays mounted between the X-ray tube and the position of the operator when he operates said controlling devices.

16. An X-ray cabinet, comprising a cabinet with a swinging member, an X-ray tube mounted on said swinging member so that by the swinging of said member said tube may be swung into or out of said cabinet, tube-controlling devices associated with said cabinet,

and a screen opaque to X-rays mounted between the X-ray tube and the position of the operator when he operates said controlling devices.

17. An X-ray cabinet, comprising a stand, a patient's seat mounted on said stand at an intermediate point in the height thereof, and a support for an X-ray tube also mounted on said stand to extend over the head of a patient sitting on said seat, said support being adjustable to make the X-ray tube co-operate with said patient.

18. An X-ray cabinet, comprising a stand, a patient's seat mounted on said stand at an intermediate point in the height thereof, a support for an X-ray tube also mounted on said stand to extend over the head of a patient sitting on said seat, said support being adjustable to make the X-ray tube co-operate with said patient, and controlling devices for said X-ray tube carried by said stand.

In witness whereof, I have hereunto set my hand at Indianapolis, Indiana, this 20th day of January, A. D. one thousand nine hundred and nineteen.

EDWIN L. EDWARDS.
